UNITED STATES PATENT OFFICE.

ARTHUR BUTTS, OF BRAZIL, INDIANA.

SAFETY-CATCH FOR ELEVATORS.

1,177,170.

Specification of Letters Patent. Patented Mar. 28, 1916.

Application filed January 19, 1915. Serial No. 3,081.

To all whom it may concern:

Be it known that I, ARTHUR BUTTS, a citizen of the United States, residing at Brazil, in the county of Clay and State of Indiana, have invented certain new and useful Improvements in Safety-Catches for Elevators, of which the following is a specification.

It is an object of the invention to give an improved construction of safety grips for elevators, and one particularly applicable to mine cages, which will be cheap to produce, efficient in action, and durable.

It is a particular aim to present such a device the operation of which will be simple and readily understood without expert mechanical knowledge. Further, it is purposed to enable the renewal of certain important parts which are subject to wear, without the dismantling of the mechanism, and by persons without great mechanical ability.

It is a most important object to provide a friction block, or gripper, constructed, and with a mounting to permit its removal and replacement without the use of tools or special appliances.

Additional objects, advantages and features of invention will appear hereinafter in the construction, arrangement and combination of parts there described, or shown in the drawings, in which,

Figure 1 is a side elevation of a cage equipped with one of the possible embodiments of my invention, Fig. 2 is a perspective view of the guide piece with the friction blocks removed, Fig. 3 is a detail of the friction block, Fig. 4 is a similar view showing the wear face, Fig. 5 is a fragmentary view of one side of the guide channel in the guide piece, illustrating the initial movement of the friction block for removal.

There is illustrated formally a cage 10 mounted between the usual guides 11, and including the two side pieces 12 to which the floor 13 is attached in a suitable manner, and a cross beam 14 fixed across the upper ends of the side pieces. At the lower parts of the side pieces 12 guide blocks 15 are mounted, engaged with the respective guides 11, while at the upper ends of the side pieces 12 guide pieces 16 are mounted, which comprise castings each including the main body portion 17 extending vertically, and having a vertical channel 18 in its outer side receiving one of the guides 11, and having

suitable openings therethrough for securing it directly to the side pieces 12. The casting also includes lateral extensions 19 secured to the cross beam 14, between which and the body portion 17, which is of greater thickness, there are extended strengthening webs 20. Intermediately of the length of the channel, recesses of triangular form are formed at each side, in the upper or hypotenuse surface of which there is formed a dove-tail groove 22 extending longitudinally thereof from the upper end, the sides of which are widened at its lower part as at 23, for a purpose to appear. Alined with these grooves slots 24 are formed through the outer sides of the guide pieces, in which there are mounted levers 25 constructed to oscillate in the medial vertical plane of the recesses, and having projecting outer end portions 26 to which are connected heavy contractile springs 27, fastened to the lower parts of the side pieces beneath the levers and tending to hold them at the lower limit of their movement. Connected also to these ends of the levers there are cables 28, extending upwardly and over pulleys 29 at the upper parts of the guide pieces 17, from whence they are extended to the main lifting cable 30 connected directly to the cross beam in a customary way, the cables 28 being connected to the main cable 30 a distance above the cross beam, whereby the outer ends of the levers 25 are normally held upward against the action of the springs 27. The latter are of sufficient strength to draw the cables 28 downwardly in case the tension on the cable 30 falls below a predetermined minimum. The inner ends 31 of the levers are arranged to engage the lower sides of the recesses 21 when approximately horizontal, and stop short of the sides of the channel 18 a suitable distance.

Engaged in and conforming to the shape of the recesses 21, there are friction blocks 32 having an inner vertical guide engaging face 33 formed with inclined grooves 34, extending outwardly from the middle on each side and inclined upwardly toward their outer ends. These grooves are closely spaced throughout the length of the blocks, in parallel relation. The height of the blocks is less than that of the recesses, and they are formed with central grooves 35 across their bases alined with and receiving the inner ends of the levers 25, whereby

their lower parts are held against lateral displacement from the recesses. On their inner or inclined sides, the blocks are provided with guide heads 36, circular in form 5 and conforming in section with the upper parts of the grooves 22 so as to fit snugly yet freely therein for sliding movement of the blocks. With the inner ends of the levers 25 at the lower limit of their movement, 10 the vertical sides of the blocks lie clear of the guides 11 within the recesses 21, and may be lifted so that their lower ends will clear the lever ends 31. They may then be swung outward at the bottom on the heads 36 as pivots, and when extended laterally from the recesses 21 at right angles to the grooves 22 or nearly so, the heads 36 may be moved downwardly in the grooves to the enlarged portion 23; when they may 15 be disengaged and the blocks removed. Replacement may be accomplished by the reverse operation.

By this construction and arrangement the blocks may be removed with great ease for 25 cleaning or renewal, and this is of great importance and value, as the accumulation of heavy partly dried grease, oil, and gummy substances, make the device liable to clogging or becoming gummed so that its 30 operation would be uncertain. This difficulty is experienced generally in devices of this kind, and by enabling the removal of the blocks manually and without tools the cleaning of the device will be better attended to, because it is not arduous and will 35 not take an objectionable amount of time.

The grooves 34 serve the important function of causing grease and oil encountered by the block to pass to the sides, whereby 40 the gripping action will be more efficient because of greater friction, due to removal of lubricant.

The simplicity and adaptability of the device to manufacture at a low cost will be 45 obvious.

The function of the device in operation will be readily understood by those versed in the art, without detailed explanation. It is sufficient to say that when properly 50 installed upon an elevator, should the lifting cable 30 or the equivalent, become broken,

or the hoisting mechanism fail, allowing the cage to fall, the decrease of tension permitting such fall would permit the springs 27 to operate the levers 25, forcing the blocks 32 upwardly until they engage the guides 11 55 their frictional engagement therewith causing them to bind and wedge against the guides until the cage is checked.

What is claimed is:

1. An elevator safety appliance of the class described comprising a body member having a guide receiving channel therein, recesses being formed at the sides of the channel having upwardly convergent sides, 65 a dove-tail groove being formed longitudinally at the upper part of each of said sides having an enlargement at the lower part, friction blocks having headed members engaged slidably in the grooves shaped to permit pivotal movement of the blocks thereon, operative means and connections for moving the block under diminution of tension in a hoisting cable including a member movable beneath and against the under side 70 of the block.

2. An elevator safety appliance of the class described comprising a body member having a guide receiving channel, at least one side of the channel being formed with 80 a lateral enlargement having an inclined side convergent toward the channel at the upper part, a dovetail groove being formed in the upper part of the inclined side having an enlargement at its lower part, a friction 85 block slideable in the enlargement of the channel having an outwardly enlarged projection engaged snugly and slidably in the dovetailed groove, the block being recessed at its under side, a lever pivoted on the body, having one end removably set in said recessed side of the block, resilient means engaged with the lever for the action described, and means to connect the lever to a 90 hoisting cable.

In testimony whereof I have affixed my signature in presence of two witnesses.

ARTHUR BUTTS.
